TOP HOUSING OF A WATER-SKI TOWING DEVICE

Miroslav Uroshevich, 2505 Fleetwood Ave.,
Cincinnati, Ohio 45211

Filed Oct. 4, 1973, Ser. No. 403,409

Term of patent 14 years

Int. Cl. D12—14
U.S. Cl. D34—41

FIG. 1 is a perspective of the top housing of a water-ski towing device.

FIG. 2 is a front view of the top housing of a water-ski towing device; and

FIG. 3 is a left side view of the top housing of a water-ski towing device.

The elements shown in broken lines are included only for illustrative purposes.

I claim:

The ornamental design for the top housing of a water-ski towing device, as shown and described.
